(54) TANNING LEATHER

(76) Inventor: Isaac Dawes

Isaac Davies, Crookham farm Maryland.

Letters Patent.

The Schedule referred to in these Letters Patent and making part of the same, containing a description in the words of the said Isaac Davies himself of his improvement in Tanning.

Be it known that I, Isaac Davies, living on Crookham Farm Montgomery County, and State of Maryland have made an improvement in Tanning; which is described as follows:—

The skins to be tanned are tanned in the usual way. When tanned, they are hauled and fleshed as usual; they are then hung in the bats upon pegs or nails as close as they can be put without pressing one each other and there to remain till they are fit to work in the bark. They are then to be clean worked out and rinsed in water; then being in the tanks upon pegs or nails, as in before described in weak sour liquor for two or three days. They are then to be removed into a stronger liquor and hung on pegs or nails as before, there to remain, four or five days.—

Then make a very strong liquor of black oak bark into which introduce one pound of blanched or other salts for a quart of about thirty sides, also add about 3 bushels of bark at the bottom of the vat and one on the top; into this vat hang the sides as before mentioned, there let them remain about three weeks; likewise lay four 36A sides on the top of the vat to prevent the strength of the liquor from evaporating.

The bats to be covered with boards or bags

When the hides are removed the different salts can be used as weak liquors for the next hides to be tanned.

What I claim as my invention is the before described method of tanning leather, by which it can be tanned in much less time, less labour and is equally good with that tanned by the usual mode.

In witness whereof I have hereunto subscribed my name before two witnesses and made affirmation to the same this 16th day of April 1801.
